RAILWAY CAR COUPLER OPERATING DEVICE
Boleslaus J. Halon, Lansing, Ill., assignor to Stanray
Corporation, Chicago, Ill., a corporation of Delaware
Filed Sept. 13, 1963, Ser. No. 308,900
5 Claims. (Cl. 213—166)

This invention relates to coupler operating devices for railway cars and has reference to a particular type of lever for operating the coupler, and to a bracket for rotatably supporting the outer end of the lever for convenient manipulation by a trainman from the side of the car.

In an attempt to eliminate as much loss and damage as possible to lading carried by railroads, ways and means of reducing same have been studied. Most of this damage comes from shocks due to service movements of the car, and accordingly there has been developed a sliding center sill underframe with a cushioning arrangement for railway cars which would have little or no recoil and which would allow a considerable amount of travel of the sliding sill at all impact speeds, thereby to better protect the commodities carried within the car.

Damage to lading is the result of too rapid acceleration and deceleration of the car in which it is carried. To reduce the effect of too sudden acceleration and deceleration of the car, greater distance and time to effect the change in velocity are required. This necessitated the use of a sliding center sill with a cushioning device therein.

Couplers installed in this type of center sill arrangement have been made to move forward and backward a greater and greater distance. In the ordinary draft gear arrangement, they would move some five to six inches, but with the sliding center sill types, the couplers have been made to move forty inches and more. This meant greater side swing of the couplers and wider mouthed strikers to accommodate side movement of the coupler when cars are rounding curves. The tendency is to build longer cars resulting in greater overhang from truck centers to couplers and therefore greater side travel is required at the coupler to negotiate railroad track curves.

It is therefore the principal object of this invention to provide an operating lever for a bottom operated coupler, mounted in an underframe construction having a moderate cushion, resulting in excessive relative longitudinal movement between car body and coupler. The operating lever must therefore accommodate this movement of the coupler in relation to the car end. When the draft gear is in extreme buff position, the operating rod must retract to about forty-two inches, and when in extreme draft position, must extend to some six feet or more.

It is a further object of the invention to provide a coupler operating device which will meet these conditions with a minimum of parts and expense, with simplicity and efficiency in operation.

Other objects and advantages of the invention will appear in the following detailed description thereof.

Referring now to the accompanying drawing forming part of this application and wherein like reference characters indicate like parts:

FIGURE 1 is a top plan view of the invention showing in dotted lines the full buff left and full draft right positions of the lever and the angling of the lever to accommodate these positions;

FIGURE 2 is a front view of FIGURE 1 slightly in perspective;

FIGURE 3 is a front view on the line 3—3 of FIGURE 1;

FIGURE 4 is a section on line 4—4 of FIGURE 3;

FIGURE 5 is a section on line 5—5 of FIGURE 3;

FIGURE 6 is a top plan view of the bracket of FIGURE 1 slightly enlarged;

FIGURE 7 is a view on line 7—7 of FIGURE 6; and

2

FIGURE 8 is a front view of a modified form of the invention.

The prior art discloses coupler operating devices for use with A. A. R. type E and earlier couplers, which devices are constructed of a plurality of parts for translating rotary motion from one part to the other and to the coupler rotor for operating the coupler. Two of these devices are shown in Patents 1,926,117 and 1,981,179, the former being owned by my assignee's predecessor company and the latter being licensed thereto. In each case it can be shown that such devices are not operable with the recently developed sliding center sill with cushioned underframe having couplers with shanks varying in length from 21 $\frac{1}{4}$ " to 34 $\frac{1}{2}$ " and wherein the couplers themselves move outwardly from extreme buff position to approximately 46" and may swing laterally up to about 15° on either side of the longitudinal center of the car. Furthermore they will not transmit torque within a reasonable movement of the handle.

Referring now to the drawings, 10 indicates the end of a car to which the device is applied and 12 indicates the striker to which the car coupler is assembled and which is attached to the center sill of the car. Since the coupler operating rod or lever is pivotally attached at one end to the lock lifter of the coupler for rotating and lifting the lock lifter to unlock the coupler, and at the other end is mounted in a bracket secured to the end of the car, it is necessary that the rod be constructed of telescopic parts to accommodate the various positions of the coupler.

My operating rod or lever is formed of two parts, a handle lever 14 and a hook lever 16. The bracket for mounting the outer part of the lever to the car is shown generally at 18. This bracket comprises a Z-shaped member which includes a flat rectangular portion 20, which is secured to and extends downwardly with respect to the end 10 of the car body, a horizontally disposed portion 22 which extends perpendicularly to portion 20, and a flange 24 extending in substantially arcuate form downwardly from the outer edge of the horizontal portion 22, forming an abutting flange or stop to limit the clockwise rotation of the handle. Upon the horizontal portion 22, adjacent the flange 24 are secured the ends of a U-shaped clevis 26 which extends outwardly beyond the flange 24 so that the outwardly extending portion forms an eye on a vertical axis and the outer end of the operating rod may be pivotally united thereto.

The outer or handle lever 14 of the operating device comprises a downwardly extending grip portion 28 having an inturned lower end. The upper end of the grip portion is bent backwardly upon itself forming an eye 30 which surrounds the clevis 26 and thus makes a slideable and pivotal connection thereto. Below the eye 30 the handle portion is turned laterally into an elongated straight portion 32, which, when mounted on the car, extends more than half the distance to the coupler. The hook lever 16 is composed of an elongated straight portion 34 of about the same length as portion 14, and its inner end terminates in a hook 36 which is designed to hook into and operate the lock lifter of a car coupler, upon rotation of hook lever 16. The lengths of the two portions are such that when the coupler is in extreme draft position, there will still be sufficient overlap of the portions to transmit torque in operating the coupler. The outer end of portion 34 is provided with a U-shaped clip 38, the end edges of the sides of which are welded to opposite sides of the end margin of the portion 34. This clip also carries an anti-friction roller 40 mounted within the clip between the two sides thereof adjacent the bend therein. The portion 32 of the handle lever 14 extends through the clip 38 under the roller 40 so that the hook

lever 16 rolls on the portion 32 in telescoping therewith. The inner end of the portion 32 is also provided with a U-shaped clip 42 which extends around the portion 34 of the hook portion and the free edges of the ends of the clip 42 are welded to opposite sides of the end of portion 32. The end of portion 32 extends between the edges of the clip 42 about half way so that there remains room for the pivotal mounting between the sides of clip 42 of another anti-friction roller 44 which rolls on section 34 of hook lever 16.

Spaced outwardly from the clip 42, between it and the clip 38 is a guide clip 46, which is U-shaped like the others and extends around the portion 34, up and engaging opposite sides of portion 32, where the free ends of said clip 46 are welded to portion 32.

When the handle and hook levers are assembled as shown, the rods are supported about $\frac{1}{4}$ " apart, and when rotary motion is applied to the handle lever 14 by moving handle 28 in a counter clockwise direction, the clips engaging the hook lever 16 will cause similar rotation to be imparted thereto which is translated to the lock lifter of the coupler to operate same.

The alternate form of the invention shown in FIGURE 8 is practically the same as that shown in FIGURE 2. Identical parts are given the same reference numeral in each view. In FIGURE 8 the inner end of the handle lever is provided with a U-shaped clip 50, the free edges of the ends of which are welded to lever 32. This clip surrounds the hook lever portion 34 and between the sides of the clip is rotatably mounted a roller 52 which rolls on portion 34 as the two rods move relative to each other. The intermediate U-shaped clip 54 also surrounds the portion 34 and the free edges of the ends of which are welded to the opposite sides of the portion 32. Between the sides of this clip 54 a similar anti-friction roller 56 is mounted, which is positioned under the portion 34 of hook section 16. The outer or guide clip 58 is also U-shaped, encircling the portion 32, and the free ends of the sides of which are welded to opposite sides of portion 34 of lever 16.

Each lever is supported by a roller on the other lever and thus they may easily telescope in following the movements of the coupler.

This invention is in the direction of simplicity rather than complexity, there being an absolute minimum of parts and material to accomplish the purpose.

It has been found in practice that the combination of two roller clips and one guide clip stabilizes the levers when torque is applied and eliminates practically all slack between the two levers during operation of the device.

From the foregoing it is apparent how the device operates. When hook 34 is engaged in the lock lifter of a coupler and the handle 28 is mounted in bracket clevis 26, with the depending handle portion against flange 24, operation of the handle 28 in a counterclockwise direction will correspondingly rotate lever 16 which in turn will impart similar rotation to the lock lifter and operate the coupler.

I claim:

1. The combination with a railway car having a sliding center sill underframe with cushioning medium, a longitudinally and laterally movable coupler mounted therein for relatively long longitudinal and wide lateral movements, a lock lifter in said coupler for operating same and a bracket secured to the end of a car body at one side thereof, said bracket having a horizontal section disposed

substantially normally to said car end, of means to operate said coupler from the side of the end of said car, said means consisting of a clevis secured to said horizontal section of said bracket and extending therebeyond to form an eye disposed on a vertical axis, a handle section having an eye formed therein mounted within the eye of said clevis, the handle depending from said clevis, said handle section having an elongated body portion extending laterally therefrom toward said coupler, a second section having a hook at one end thereof for attachment to said lock lifter, and a body portion overlapping the body portion of said handle section, the end of each section having a U-shaped clip secured to opposite sides thereof and extending around the other section, whereby said sections may slide longitudinally with respect to each other responsive to movements of said coupler.

2. The structure of claim 1, each clip having an anti-friction roller mounted therein for rolling along the body portion.

3. The structure of claim 1, and a U-shaped guide clip secured at opposite sides of one section and extending around the other section for stabilizing the sections when they move relative to each other.

4. A lock lifter operating lever for operating the coupler of a railway car coupler comprising a rotatable lever including a handle section having an eye formed therein on an axis parallel to said lever for mounting same on said car, a second section having a hook at its inner end for attachment to said lock lifter, said sections overlapping each other, each section having a U-shaped clip secured to opposite sides thereof and extending around the other section, a guide clip secured to opposite sides of one section and extending around the other section, an anti-friction roller mounted within each U-shaped clip for rolling along said sections, whereby said sections may slide longitudinally with respect to each other responsive to movements of said coupler.

5. A lock lifter operating lever for operating the coupler of a railway car coupler comprising a rotatable lever including a handle section having an eye formed therein on an axis parallel to said lever for mounting same on said car, a second section having a hook at its inner end for attachment to said lock lifter, said sections overlapping each other, a pair of U-shaped clips each secured to opposite sides of a section and extending around the other section, an anti-friction roller mounted within each of said clips and rollable along a section, and a guide clip surrounding one section and attached to the other section whereby said sections may slide longitudinally with respect to each other, and the said roller clips and guide clip stabilize said levers when torque is applied thereto.
